US0D1046446S

(12) **United States Design Patent** (10) Patent No.: **US D1,046,446 S**
(45) Date of Patent: ** Oct. 15, 2024

(54) **BAG**

- (71) Applicant: **YETI Coolers, LLC**, Austin, TX (US)
(72) Inventors: **Roy Joseph Seiders**, Austin, TX (US);
Dustin Bullock, Austin, TX (US)
(73) Assignee: **YETI Coolers, LLC**, Austin, TX (US)
(*) Notice: Patent file contains an affidavit/declaration
under 37 CFR 1.130(b).
(**) Term: **15 Years**
(21) Appl. No.: **29/770,838**
(22) Filed: **Feb. 17, 2021**
